UNITED STATES PATENT OFFICE.

JAMES C. DAWSON, OF WEBSTER GROVES, MISSOURI.

LOOSE-LEAF BINDER.

Application filed December 13, 1923, Serial No. 680,309.

To all whom it may concern:

Be it known that I, JAMES C. DAWSON, a citizen of the United States, and resident of Webster Groves, county of St. Louis, and 5 State of Missouri, have invented certain new and useful Improvements in Loose-Leaf Binders, of which the following is a specification, and which are illustrated in the accompanying drawings, forming a part 10 thereof.

This invention relates to loose leaf binders and has for its principal objects to provide improved articulation between the rods carrying the paper holding prongs; to maintain the prongs in alignment; to permit easy 15 assembly without the aid of special tools; and to reduce the cost of manufacture to a minimum.

Further objects and advantages of the invention will become apparent as the description is read in connection with the accompanying drawings illustrating a selected embodiment of the invention, and in which

Fig. 1 is a plan view of a loose leaf binder 25 made according to the invention and with the backs broken away;

Fig. 2 is an inverted plan view of the paper holding mechanism proper;

Figs. 3, 4 and 5 are sectional views taken 30 on the lines 3—3, 4—4 and 5—5 respectively of Fig. 1;

Fig. 6 is a perspective view of a portion of one of the rods;

Fig. 7 is a perspective view showing the 35 assembled binder equipped with a cover for the paper-holding devices that serves to give the binder a neat and finished appearance, and

Fig. 8 is a cross sectional view of the cover 40 illustrated by Fig. 7, showing an oppositely disposed notch and perforation.

In the drawings a back plate is shown at 10 which may be equipped with suitable backs 11 that are broken away for convenience in illustration. The paper-holding devices include a pair of rods 12 each of which is bent at each end to form short rigid arches 13 and paper holding prongs 14. The crown portions 15 of the arches are preferably 45 made substantially straight and serve as bearing members for the rods in rotating between positions in which the prongs are opened and closed. These flat crown portions are journaled in the curved flanges 16 50 of a spring clip, or clips 17, each of which is provided with a tab 18 by which the paper-

holding devices may be secured to the back plate with rivets 19.

The spring portions of the arches are provided with mating grooves 20 which terminate in shoulders 21; and the spring portions are arranged in juxtaposition with the mating grooves forming bearings for interlocking and antifriction rods 22 the ends of which cooperate with the shoulders 21 to hold the prongs 14 always in proper alignment.

The tabs 18 for the clip or clips 17, bend downwardly at 23 to locate the body portion of the tabs parallel to the bottom surface of the fastening devices and also to make a neat closure for the ends of the bearings in which the rods are mounted. One of the flanges 16 is perforated at 24 to permit the free movement of the corresponding prong 14 and the other flange is notched at 25 opposite to the perforation to permit similar movement of the opposite prong.

It has heretofore been proposed to interlock the rods by providing tongues on one of the rods and grooves on the other. In certain of these prior devices the rods were made rights and lefts, one having the grooves and the other the tongues. This increased the cost of manufacture and was generally 55 objectionable. In others of these devices the rods were grooved at one end and tongued at the other so that the two rods were duplicates, but it was found that this produced a peculiar twisting strain in opening the 90 prongs, which threw them out of alignment and otherwise interfered with the proper operation of the devices. The interlocking by means of the rods 22 fitting in the mating grooves 20 overcomes these and other 95 objections to prior constructions. In addition these rods serve as excellent bearings, and the ends thereof, in cooperation with the shoulders 21, prevent any longitudinal movement of one rod relative to the other, 100 thereby holding the prongs in proper alignment.

By making the arches short and rigid all tendency to distortion in opening and closing is eliminated and the quick snappy 105 movement results.

By using two short clips 17 a substantial amount of metal is saved and the assembly of the devices is facilitated. Where the trade requires a better finish a cover plate 27 (Fig. 7) may be used to cover the intermediate portion of the rods, the clips 17, together 110

with the rivets 19 and the tabs 18,—the cover being notched and perforated, as indicated at 28 and 32, to receive and permit movement of the prongs 14. The cover is preferably made of resilient material that will permit it to be sprung into and out of place at will. Thus the same paper-holding devices may be used in both the expensive and the inexpensive constructions which permits 19 a saving in manufacture and supply and is a great convenience to the dealer.

Where adjustment is required the intermediate portions of the rods 12 may be omitted and the clips interlocked with the backs 15 after the fashion described and claimed in my copending application, Serial No. 623,690, filed March 8, 1923, and the cover may be relied upon to hold the parts in an adjusted position.

20 If perforations 24 were used in both flanges 16, the assembly of the rods in the clips would require skill and intelligence of an order that is expensive, but by using one perforation 24 and one notch 25, substantially as shown, the assembly is made so easy that ordinary labor can be employed. At the same time the tie effected by the piece of material 29 at the extreme outer edge of the flange having perforation 24 braces the neck 30 31 between the notch and the perforations, and gives sufficient rigidity and strength to the structure.

The notches 28 in the cover are preferably both on the same side, and the perforations 32 opposed thereto on the opposite side. In assembling the cover the prongs 14 are inserted through the perforations, and then pressure is applied to spring the cover in place. The metal back of the perforations 40 32 cooperates with the corresponding prongs and prevents the cover from riding up and out of position.

I claim as my invention:

1. In a loose leaf binder, the combination 45 of a pair of rods, each bent to form an arch and a paper-holding prong adjacent thereto,

a spring clip in which the arches are mounted to form a toggle, adjacent portions of the arches having mating grooves terminating in shoulders and a rod seated in said grooves 50 and cooperating with the shoulders to hold the paper-holding prongs in alignment.

2. In a loose leaf binder, the combination of a pair of rods, each bent to form an arch and a paper-holding prong adjacent thereto, 55 a spring clip in which the arches are mounted to form a toggle with the crown portions of the arches spaced apart and the spring portions of the arches lying adjacent to each other, said spring portions having mating 60 grooves therein terminating in shoulders and a rod seated in said grooves and cooperating with the shoulders to maintain the prongs in alignment.

3. In a loose leaf binder, the combination 65 of a pair of rods each bent to form an arch and a paper-holding prong adjacent thereto, a spring clip having edges shaped to form bearings for portions of said rods, one of said edges being perforated to receive a 70 prong and the other edge being notched opposite to the perforation to receive the corresponding prong.

4. In a loose leaf binder, the combination 75 of a pair of rods each bent at each end to form an arch and a paper-holding prong adjacent thereto, a pair of spring clips each having edges shaped to form bearings for portions of said rods, the rods being assembled in the clips with the arches arranged 80 to form toggles, said clips having projections thereon by which they may be secured to a back plate and a resilient cover plate adapted to be sprung into position over the clips to cover the clips and the rods. 85

5. A loose leaf binder, the combination of paper holding devices, including pairs of separable prongs, and a spring cover having oppositely disposed notches and perforations, each pair of the said prongs extending 90 through a notch and perforation.

JAMES C. DAWSON.
